UNITED STATES PATENT OFFICE.

CARL ANTON SPORRONG, OF STOCKHOLM, SWEDEN, ASSIGNOR, BY MESNE ASSIGNMENTS, TO ERNST LUNDGREN AND ALFRED RICHARDSON, OF BROOKLYN, NEW YORK, AND JAMES WHITESIDE, OF NEW YORK, N. Y.

APPARATUS FOR TEACHING GUN PRACTICE.

SPECIFICATION forming part of Letters Patent No. 707,729, dated August 26, 1902.

Application filed September 4, 1901. Serial No. 74,297. (No model.)

To all whom it may concern:

Be it known that I, CARL ANTON SPORRONG, a subject of the King of Sweden and Norway, and a resident of Stockholm, Sweden, have invented certain new and useful Improvements in Apparatus for Teaching Gun Practice, of which the following is a specification.

The object of my invention is to provide means whereby the practical operations of target-shooting may, so far as the drill exercise is concerned, be carried on without the waste of ammunition and the dangers incident thereto and also without the long range necessary to the common practice.

15 The invention comprises, essentially, a universally-jointed gun-support, which gun may be a dummy or false gun and is subject while on said support to the manipulations of the practitioner, said support allowing practically 20 the same deviations of the gun when being sighted as in the common practice, with means for transmitting the deviations to a pointer so connected to the gun-support as to keep in such alinement relatively to the line of the 25 gun-sight as to point to the same object, and a clamping device which is automatically actuated simultaneously with and is set in operation by the pulling of the trigger and instantly locks all the parts fast in the positions 30 they occupy at the instant the trigger is pulled, so that the pointer shows with relation to a fixed center representing the bull's-eye of the target the deviations due to the practice of the unskillful operator as they are 35 shown on the ordinary target.

The invention also comprises various details of construction in the apparatus, as hereinafter described, reference being made to the accompanying drawings, in which—

40 Figure 1 is a perspective view of my improved apparatus as set up for use. Fig. 2 is a central vertical section. Fig. 3 is a horizontal section taken on the line 33 of Fig. 2. Fig. 4 is a vertical section on the line 44 of Fig. 2. 45 Fig. 5 is a detail showing the clamp-setting and tripping lever.

A represents the substitute gun, and a represents a support of trough-like construction in which the gun may be placed so as to be

gripped, together with the gun, by the left hand, as the ordinary gun is gripped when placed against the shoulder for use, while the right hand grips the part *l* only of the stock of the gun. The support *a* is at its rear end mounted on the top of a vertical pivot-standard *b*, 55 which at about the middle of its length has support in a block *c*, through which it is fitted so as to rotate, said block being carried by trunnion-pivots *d* in housings *e*, set upright on a base-plate *r*, so that the stock may shift 60 in a vertical plane for adjustment as to elevation of the trajectory, while rotation of the standard *b* accommodates the lateral range.

The block *c* carries a step-bearing *f* for the pivot *g* of the lower end of the standard *b*, 65 said bearing being suspended a suitable distance below by hangers *h*. The false gun is thus mounted so as to work universally in the hands of the operator practically the same as a gun wholly supported in the hands, and 70 with the stock so mounted a pointer *i*, located below and in alinement with it in a vertical plane and universally pivot-jointed at *j*, is coupled to the standard *b*, so that the pointer automatically follows the line of the 75 gun-sight in all the deviations it may make when manipulated by the operator, and when the gun is accurately pointed with relation to the object aimed at the said pointer registers with a bull's-eye mark *k*, fixedly set on 80 a transparent support *m* directly in front of the pointer, and thus shows that aim was correct, and whatever deviation there may be of the pointer relatively to this mark represents the measure of the inaccuracy of the operator. The connection of the pointer-staff *i* with the standard *b* is preferably by means of a metallic strip or wire spring 12, having several coils 13 and a rigid arm 14 interposed between said spring and the standard for an 85 elastic connection; but this may be modified at will. The universal fulcrum-joint pivot of the pointer-staff *i* may be constructed in any approved way. It is to be understood that the pointer is not necessarily located 90 under the gun nor in its vertical plane. In regard to these particulars the arrangements 95 specified are only such as preferred.

To fixedly set the pointer exactly in the position occupied at the instant of pulling the trigger and retain it a short time for observation, the trigger *n*, which instead of being connected with the gun is pivoted at *o* on the support *a* back of the standard *b*, is made to release an automatic clamp, which at once rigidly arrests all movements of the gun-supporting apparatus, and thus rigidly sets the pointer in whatever relation it may be to the bull's-eye mark.

The clamp may be constructed in various ways, and I do not limit myself to any particular construction. The construction which

- 15 I represent herein as one example of such device suitable for carrying out my invention consists of the housings *e*, between which the block *c* is pivoted, being made slightly elastic in their supporting parts *e'*, the housings *e* 20 and the flange *p* of an internally-screw-threaded sleeve *q*, placed outside of one of the housings and coupled together by bolts *s*, extending through slots *t* of the block, allowing said block limited rotatory movement on its axis 25 without hindrance by said bolts, said housings being also free for slight movement along the bolts, or at least the one between the flange *p* and the block *c* must be so.

In the sleeve *q* is a clamp-operating screw 30 *u*, to one end of which, projecting from the outer end of the sleeve, a hand-lever *v* is attached, while the inner end of said screw has when screwed up contact with the housing *e*, against which the flange *p* of the sleeve *q* 35 bears. The lever *v* carries a ratchet-segment *w* on the extremity of its short arm, which engages with a pawl-bit *x* when the lever is turned by hand to the left or in the direction to retract the screw, and holds it for maintaining the relaxed condition of the clamp.

On the sleeve *q* between the flange *p* and a collar *y* is a coiled spring *z*, one end of which is secured to the flange *p* at 2 and the other end engages the short arm of the lever *v* at 45 3, said spring being so adjusted that under tension it thrusts the lever so as to tighten the clamp when the ratchet *w* is released from the retaining-pawl bit *x*. This pawl-bit *x* is carried on a lever *4*, pivoted at 5 and having 50 a spring *6* normally keeping the said bit in engagement with the ratchet *w*.

The lever *4* reaches into a recess 7 in the standard *b* just above the step-bearing of said standard, so that a rod *8* set upright in the 55 hollow axis of the standard may rest at its lower end on or slightly above the lever *4* near its free end. This rod extends upward to the top of the standard *b* or thereabout, where an arm *9* of the trigger *n* rests on it, so that when the trigger is pulled the lever *4* 60 is depressed, which releases the pawl-bit *x* from the ratchet *w*, allowing the spring *z* to act and tighten the clamp at the instant the trigger is pulled, and thus set the pointer in 65 relation to the bull's-eye *k*, showing the result of the effort of the operator to hit the object aimed at, which may be any object at a

suitable distance or a common target, if desired. The lever *4* carries a plate *21*, the breadth of which is coextensive with the lateral range of the end of the rod *8*, due to the oscillations of the block *c*, and thus insures uninterrupted connection of the two notwithstanding the oscillations. A coiled spiral wire spring *10*, located in the hollow axis of the standard *b* and surrounding the rod *8*, relieves the lever *4* of the weight of the rod for sensitive action. The lever *v* is pulled forward again and is automatically again engaged by the pawl-bit *x* for releasing the clamp 80 preparatory to the next operation.

The base-plate *r* is detachably and adjustably clamped to an arm *14*, which is similarly clamped to a post *15*, that may have any suitable support.

85 A protective inclosing case *16* is applied to the apparatus below the support *a*, and a funnel-shaped protector *17* for the pointer *i*, which projects through said case, is suitably attached thereto and carries at its outer end the before-mentioned transparent support *m*, through 90 which the pointer *i*, indicating the results of the efforts of the practitioners, is seen.

95 For enabling the instructor to observe the pointer from the positions he occupies in conducting the practice a mirror *18* is hinged to the outer end of the pointer-protector *17*, as indicated at 19, which may be set at any suitable angle for reflecting the images of the bull's-eye and pointer in the directions for 100 being so observed, thus exhibiting to him the effect of every effort of the operator and affording him opportunities of instantly pointing out to the operator his inaccuracies in particular and in general tendencies such as 105 has in no way or by any means been heretofore provided for. The hinge *19* may be connected to the protector by a sliding bar *20*, whereby it may be set outward from the end of the protector more or less to facilitate the 110 use of the reflector.

What I claim as my invention is—

1. The combination of the gun-support adapted for the application of a gun for use in connection with it, as in sighting the gun 115 and shooting, and provided with a trigger for use in lieu of the gun-trigger, the universally-jointed mounting of said support, a pointer having a universally-jointed support, and connected with the gun-support so as to maintain parallelism with the deviating line of the gun-sight, a bull's-eye mark located in the line which the pointer occupies when the gun is truly sighted with relation to the object aimed at, an automatic clamp to lock the 120 parts in the positions occupied when the trigger is pulled, setting devices for holding the clamp in readiness for action, and tripping mechanism for said holding devices actuated by the trigger.

125 2. The combination of the gun-support adapted for the application of a gun for use in connection with it, as in sighting the gun and shooting, and provided with a trigger for 130

- use in lieu of the gun-trigger, the universally-jointed mounting of said support, a pointer having a universally-jointed support, and connected with the gun-support so as to maintain parallelism with the deviating line of the gun-sight, a bull's-eye mark located in the line which the pointer occupies when the gun is truly sighted with relation to the object aimed at, and having a transparent support, 5
- 10 an automatic clamp to lock the parts in the positions occupied when the trigger is pulled, setting devices for holding the clamp in readiness for action, and tripping mechanism for said holding devices actuated by the trigger.
- 15 3. The combination of the gun-support, trigger connected with said support, universally-jointed mounting of said support, a pointer having a universally-jointed support, and connected with the gun-support so as to maintain parallelism with the deviating line of the gun-sight, automatic locking-clamp for said support, setting devices for holding said clamp in readiness for action, tripping-lever of said setting devices, tripping-lever-actuating rod 20 carried in the gun-support-mounting devices, the arm of the trigger adapted to actuate said rod, and means to retire the rod.
- 25 4. The combination of the gun-support, trigger connected with said support, universally-jointed mounting of said support, a pointer having a universally-jointed support, and connected with the gun-support so as to maintain parallelism with the deviating line of the gun-sight, automatic locking-clamp for said support, means for releasing said clamp, setting devices for holding said clamp in readiness for action, tripping-lever of said setting devices, tripping-lever-actuating rod carried 30 in the gun-support-mounting devices, the arm of the trigger adapted to actuate said rod, and means to retire the rod.
- 35 5. The combination of the gun-support and
- its standard, the block and the step-support carrying the standard, housings carrying the block-pivots and adapted to clamp the block, 45 clamping-sleeve and bolts connecting said sleeve and housings, clamping-screw, screw-actuating lever and spring, the screw setting and tripping devices, the trigger of the gun-support adapted for actuating the tripping devices and a pointer having a universally-jointed support, and connected with the gun-support so as to maintain parallelism with the deviating line of the gun-sight. 50
6. The combination with the universal-joint-supported gun-support which is subject to direct manipulations of the operator in firing the gun, of the universal-joint-supported pointer, means connecting the gun-support and pointer whereby parallelism of the pointer with the deviating line of the gun-sight results from the deviations of the gun and a substitute bull's-eye mark in close proximity to the pointer. 55
7. The combination with the universal-joint-supported gun-support, the universal-joint-supported pointer, and means connecting the gun-support and pointer whereby parallelism of the pointer is maintained with the deviating line of the gun-sight, of the 60 bull's-eye mark located in the line which the pointer occupies when the gun is truly sighted with relation to the object aimed at, and an adjustable mirror adapted for reflecting the images of the pointer and the bull's-eye 65 into the visual range of the instructor in the requisite proximity to the operator for directing him. 70
